US00D908319S

(12) **United States Design Patent** (10) **Patent No.:** **US D908,319 S**
Maier (45) **Date of Patent:** **** Jan. 26, 2021**

(54) **GARMENT**

(71) Applicant: **ASSOS OF SWITZERLAND GMBH,**
San Pietro di Stabio (CH)

(72) Inventor: **Roger Maier**, Carona (CH)

(73) Assignee: **ASSOS OF SWITZERLAND GMBH,**
San Pietro di Stabio (CH)

(**) Term: **15 Years**

(21) Appl. No.: **29/647,750**

(22) Filed: **May 15, 2018**

Related U.S. Application Data

(62) Division of application No. 29/605,740, filed on May 30, 2017, now Pat. No. Des. 853,086.
